The ornamental design for a face mask strap, as shown and described.

DESCRIPTION

FIG. 1 is a front perspective view of a face mask strap according to my new invention and showing the strap attached to a face mask. The face mask is shown in dotted lines for environmental purposes only;

FIG. 2 is a side elevational view thereof, the opposite side being a mirror image;

FIG. 3 is a front elevational view of the face mask strap shown in a flat position;

FIG. 4 is a top plan view thereof, the bottom plan view being a mirror image; and,

FIG. 5 is a back elevational view thereof.
